ATTORNEY

UNITED STATES PATENT OFFICE.

JOHN R. DAVIS, OF BRISTOL, WISCONSIN.

WHIFFLETREE-HOOK.

SPECIFICATION forming part of Letters Patent No. 322,527, dated July 21, 1885.

Application filed May 27, 1885. (No model.)

To all whom it may concern:

Be it known that I, JOHN R. DAVIS, a citizen of the United States, residing at Bristol, in the county of Dane and State of Wisconsin, 5 have invented a new and useful Improvement in Whiffletree Safety-Hooks, of which the following is a specification.

The advantages secured by the use of my device are facilities for rapidly hitching to or 10 detaching the horse or other animal from the vehicle or implement, as well as the possession of means for so securing the harness-trace to the whiffletree, that the same when in use will not be liable to be easily unhooked 15 or detached, nor the fastener be liable to get out of order or lost, the same being permanently attached to the whiffletree or other equivalent article. A further advantage which I seek to gain in the use of this device 20 is to provide by the outward curvature of my trace-hook a guard or protection for the end of the whiffletree. I attain these objects by the mechanism illustrated in the accompanying drawings, in which—

25 Figure 1 is a top view of my invention and a portion of the whiffletree to which it is attached. Fig. 2 is a cross-section end view through the line X X of Fig. 1. In this view a portion of the ring R is removed in order to 30 show the lug l. Fig. 3 is an end view of Fig. 1.

Similar letters refer to similar parts throughout the several views.

The ferrule F, the shoulder or flange S, and the lug l constitute one solid piece of metal. 35 The ring R and the hook h are also welded or cast together, forming one continuous and separate part of the device. The lug l is situated at a point diametrically opposite the point p of the trace-hook R h when held by 40 tension in the line of draft. This lug is shaped to correspond with the space a where the ring R joins the shank of the hook h, so as to allow of the convenient passage of this portion of the ring over the lug. The ring R is made to 45 ft as closely as consistent with a free radial and lateral movement. The slot or depression d in the shoulder or flange S is of about the same depth as the shoulder, and of sufficient width to allow of quickness and convenience in passing through it the point p of the hook h. The relative position of the slot d

should be such that when the hook is locked in position, as shown in Fig. 1, it cannot under any ordinary circumstances be jarred or crowded out of adjustment, while at the same 55 time it should not be placed so far back on the shoulder as to make it inconvenient to attach the harness-trace T. Approximately, the slot should be about in the relative position shown in the drawings. The ferrule F is 60 adapted to be driven on and secured upon the end of the whiffletree in the manner that such appliances are usually secured.

Having described the parts of my invention, I will now proceed to explain how it 65 operates. The part R h is first attached to the ferrule F. This is done by applying the ring R h to the inner end of the ferrule F, so that the space a is directly in line with the lug l. In this position the point p of the hook h will 70 just clear the inner end of the lug. The ring is then pushed over the lug, which is made just small enough to allow an easy clearance. This being done, the hook is re- 75 volved and the part R h or the ring-hook is locked in position, such as is indicated in Fig. 1. The ring R is permanently confined with free play between the lug l and the shoulder S. This having been done, the ferrule is 80 fitted to the end of the whiffletree and permanently secured. The spur-point p of the hook h is of about the same depth as the shoulder S, but need not be accurately constructed so long as the play of the ring R about the ferrule is not so free as to allow of the point p being canted 85 over the shoulder S.

Similar parts for the other end of the whiffletree must be made with due regard to "rights and lefts."

To attach the harness-trace, the hook is 90 turned upward until the spur-point p is opposite the depression. The ring R is then pushed up against the shoulder S, while the spur-point passing through the slot d is free. The trace is then hooked on. The hook is pushed 95 back until the spur-point clears the shoulder, when the hook is at once drawn and locked in position by the weight and tension of the harness-trace, as shown at Fig. 1. In this position it is impossible for the trace to become unhooked. The curvature of the hook at h is purposely extended outside and beyond 100

the end of the whiffletree to act as a guard against such objects as may ordinarily be encountered; but I am aware that this guard is not in itself new and patentable, nor do I claim it as such.

What I claim as my invention, and desire to secure by Letters Patent, is—

The ferrule F, with the lug l and slotted

shoulder S, in combination with the trace-hook R h, and applied to the whiffletree W or its equivalent, substantially as described, and for the uses and purposes mentioned.

JOHN R. DAVIS.
